CLAIM

The ornamental design for a tray valve, as shown and described.

DESCRIPTION

FIG. 1 is a top perspective view of a tray valve according to our new design;

FIG. 2 is a top plan view thereof;

FIG. 3 is a cross-sectional view thereof, viewed along line 3-3 in FIG. 2;

FIG. 4 is another cross-sectional view thereof, viewed along line 4-4 in FIG. 2;

FIG. 5 is a top perspective view of the tray valve shown in FIGS. 1-4 shown in a different environment;

FIG. 6 is a bottom perspective view thereof;

FIG. 7 is a right side elevation view thereof, with the left side elevation view being a mirror image of the right side elevation view;

FIG. 8 is a top plan view thereof;

FIG. 9 is a front elevation view thereof;

FIG. 10 is a rear elevation view thereof; and,

FIG. 11 is a bottom plan view thereof.

The broken lines in the drawings define the bounds of the claimed design and form no part thereof.
